attorney.

UNITED STATES PATENT OFFICE

2,165,455

WIRE TIGHTENING AND TWISTING
MACHINEHenry Wilfred Cox, North Melbourne, Victoria,
Australia

Application February 19, 1937, Serial No. 126,719

5 Claims. (Cl. 140—93)

This invention relates to hand operated wire tightening and twisting machines of the type which is adapted to tighten a wire about a case or package by the movement of a cam or toggle which effects lateral swinging of a spring pressed arm or arms to which the wire to be tightened is temporarily secured, and has been devised to ensure efficiency of operation of the machine, to simplify the construction, and to speed up the operations of tightening and twisting the wire.

The machine of this invention includes wire-tightening instrumentalities such as disclosed in my co-pending application filed February 19, 1937, Ser. No. 126,720.

15 In the accompanying drawing which illustrates one form of the invention:

Fig. 1 is a side elevation of the machine;

Fig. 2 is a plan of the same;

20 Fig. 3 is a front elevation of portion of the machine.

A metal plate 10 having a flat under face is provided on its upper face with lugs 11, 11 for a transverse shaft which carries a hand lever 13 and a central partially rotatable block 14. The lever 13 is partially rotatable in a vertical plane 25 in forward and in backward direction, and the block is fitted with lugs 15 which are adapted to be engaged by the arms 16 of the lever 13 when the latter is swung over towards the front of the machine so that the block is partially rotated in the same vertical plane by means of the lever. Loosely mounted within the cheeks of the block is a driving gear wheel 17 which meshes with a slotted wire-twisting pinion 18 rotatably mounted 30 on lugs carried by the plate 10.

The block 14 is fitted with a pair of sliding pawls which, when the lever is in extreme forward position, slip into suitably shaped notches in the gear wheel 17 and on the return movement of the lever effect rotation of the gear wheel and of the twisting pinion 18. The pawls are automatically removed from the notches during the completion of the backward movement of the lever 13. The gear ratio of the wheel 17 and pinion 18 is arranged to produce at least three revolutions of the pinion for the limited movement of the gear wheel.

45 The lower ends of the arms 16 of the lever 13 are provided with bosses which are adapted to engage spring returned slidable blocks 19 which carry cutters to sever the excess ends of the wire when the lever is completing its backward movement.

Pivotedly mounted on the rear end of the plate 50 10 are two forwardly extending arms 20 on each

of which is independently pivoted a forwardly extending arm 21. The front end of one of the arms 21 is provided with an automatically acting wire grip 22 which forces the end of a wire to be tightened into gripping contact with a fixed post 23 on the plate 10 when the wire is being tightened. The front end of the other arm 21 is provided with a spring-pressed serrated wire gripping member 24 which forces the wire against a projecting face of the arm 21.

A two piece toggle having arms 25, 25 pivoted on a central post 26, is pivotally connected with the arms 21. The post 26 is carried by a slidable block 27 fitted with adjustable cable or chain retaining members 28.

20 A flexible wire cable 29, which may be replaced by a chain, is secured at each of its ends to the members 28 and passes under rollers 30 and through apertures 31, 32 in the block 14 so that partial rotation of the block 14 by the lever 13 effects forward movement of the block 27 and consequent straightening out of the toggle so that the arms 20 and 21 are pushed outwards from the machine and tighten the wire held by the 25 grips 22 and 24.

25 A vertically swingable double-fingered member, having one of its fingers 33 positioned to engage a lug 34 on the under face of the lever 13, is adapted to be pressed against the forward central portion of the toggle, when the lever is returning to 30 inoperative backward position, and forces the toggle backwards so that the arms 20 and 21 are returned to inoperative position when the excess ends of the wire have been severed by the cutters 35 on the blocks 19.

30 The rear portions of the arms 21 are connected with each other by means of a spring 35. This spring tends to prevent outward swinging of the arms 20 and 21 and thus tends to prevent over-tensioning of the wire. It also assists to return the toggle to inoperative position. Apparatus for automatically adjusting the effect of this 40 spring on the arms 20 and 21 is described in my co-pending application.

45 A handle 36 to assist in steadying the machine during operation and for transport purposes is secured to one of the lugs 11, and a stop 37 on the rear end of the plate 10 prevents excessive backward movement of the lever 13.

50 I claim:

55 1. In a machine of the class described, wire tightening means comprising two wire gripping devices, a pivotally mounted arm carrying one of said gripping devices, a toggle arranged to swing said arm away from said other gripping

- device, a pivotally mounted operating lever, a block rotatable by said lever, an operating connection between said block and toggle, and a lug on said lever adapted to return said toggle to inactive position.
2. A wire tightening and twisting machine comprising an operating lever swingable forwardly and backwardly, a block rotatable by said lever, a gear adapted to be coupled with said block on completion of forward movement of said lever, a wire twisting pinion in mesh with said gear, forwardly extending laterally swingable arms carrying wire grippers, a spring connected with said arms, a toggle for swinging said arms away from each other comprising a slidable block between said arms and links connected to said slidable block and arms, and an operating connection between said slidable block and rotatable block.
3. A wire tightening and twisting machine comprising an operating lever swingable forwardly and backwardly, a block rotatable by said lever, a gear adapted to be coupled with said block on completion of forward movement of said lever, a wire twisting pinion in mesh with said gear, forwardly extending laterally swingable arms carrying wire grippers, a spring connected with said arms, a toggle for swinging said arms away from each other comprising a slidable block between said arms and links connected to said slidable block and arms, a wire cutter mounted on each side of said wire twisting pinion, a boss on said operating lever adapted to operate said wire cutters during completion of its backward movement, and an operating connection between said slidable block and rotatable block.
4. A wire tightening and twisting machine

comprising an operating lever swingable forwardly and backwardly, a block rotatable by said lever, a gear adapted to be coupled with said block on completion of forward movement of said lever, a wire twisting pinion in mesh with said gear, a wire cutter slidably mounted on each side of said pinion adapted to be operated by said lever during completion of its backward movement, forwardly extending laterally swingable arms carrying wire grippers, a toggle comprising a slidable block between said arms and links connected with said slidable block and arms, an operating connection between said slidable block and rotatable block, a lug on said lever, and a rotatable member adapted to be engaged by said lug during completion of backward movement of said lever and to press against the central portion of said toggle.

5. A wire tightening and twisting machine comprising an operating lever swingable forwardly and backwardly, a block rotatable by said lever, a gear adapted to be coupled with said block on completion of forward movement of said lever, a wire twisting pinion in mesh with said gear, forwardly extending laterally swingable pivoted arms, a slidable block, toggle links pivotally connected thereto and to said arms, a forwardly extending arm pivoted on each of said first-mentioned arms and each of them carrying a wire gripper, a spring connected with the rear portions of said gripper carrying arms, an operating connection between said slidable block and rotatable block, a wire cutter mounted on each side of said pinion, and a boss on the lower part of said lever adapted to operate said cutters during completion of backward movement of said lever.

HENRY WILFRED COX.
